UNITED STATES PATENT OFFICE

ALBERT F. CRESIEN, OF WINNEBAGO, MINNESOTA.

TRACTION-ENGINE

1,120,692.

Specification of Letters Patent. Patented Dec. 15, 1914.

Application filed December 21, 1911. Serial No. 667,064.

To all whom it may concern:

Be it known that I, ALBERT F. CRESIEN, a citizen of the United States, residing at Winnebago, in the county of Faribault, State of Minnesota, have invented certain new and useful Improvements in Traction-Engines; and I do hereby declare the following to be a full, clear, and exact description of the invention, such as will enable others skilled in the art to which it appertains to make and use the same.

My invention relates to new and useful improvements in traction engines for farming implements and the object of my invention is to provide a traction engine having a single drive wheel and so constructed that the engine may be employed either for plowing, mowing, or as a means for propelling a binder as desired.

A further object of my invention is to provide a simple and efficient steering mechanism for my improved engine.

With these and other objects in view, my invention will be more fully described, illustrated in the accompanying drawings which show a preferred embodiment of my device and then specifically pointed out in the claims which are attached to and form a part of this application.

In the drawings, Figure 1 is a top plan view of my traction engine showing the same employed in connection with a binder. Fig. 2 is a side elevation of the same. Fig. 3 is a rear elevation. Fig. 4 is a fragmentary top plan showing the traction engine with the binder detached.

Referring more specifically to the drawings, in which similar reference numerals designate corresponding parts throughout, 40 10 designates in general the main frame of my traction engine which as shown, consists of spaced side members 11 and 12 connected at their forward ends by a bar 12' and by a shaft 13 and at their rear ends by a back member 14 one end of which is extended beyond the side member 12 to form the back member of an auxiliary frame 15 consisting of a side member 16 parallel to the sides 11 and 12 and having its forward portion directed inwardly as at 17 and secured to the forward end of the side member 12. Journaled in suitable bearings 18 carried by the side members 11, 12 and 16 is a drive shaft 19 upon one end of which is loosely mounted a bearing wheel 20 and upon the other end of which is keyed a traction wheel 21.

Detachably connected to the forward ends of the side members 11 and 17 of the frame are the free ends of the rearwardly diverging arms 22 of a standard 23 which standard, extends forwardly and downwardly and terminates in a ball bearing member 24 engaged in a bearing socket 25 carried by the rear portion of the frame 26 of a conventional form of binder 27, said socket being 60 secured to the frame at a point adjacent the bull wheel 28 of the binder.

Mounted upon the frame is any preferred form of explosive engine conventionally shown at 29 and having a crank shaft 30 70 upon one end of which is mounted a fly wheel 31. A gear wheel 32 is keyed upon the shaft 19 and a train of reducing gears designated as a whole by the numeral 33 connect between the crank shaft of the engine 75 and the gear 32 to rotate the shaft 19 to propel the device.

As a means for steering the device I have provided a steering rod 34 one end of which is pivoted to the rear portion of the frame 80 of the binder as shown at 35 and the other end of which is provided with a plurality of rack teeth 36 adapted to mesh with the teeth of a spur gear 37 keyed upon a vertical shaft 38 the upper end of which is provided with 85 a hand wheel 39. The toothed end of this steering rod is passed through suitable guides 40 by means of which its teeth are held in engagement with the teeth of the gear and as will be readily seen any turning 90 of the hand wheel will act through the steering rod to swing the binder upon its bull wheel as a pivot.

Pivoted to the side member 11 of the frame is a hand lever 41 provided with a locking pawl 42 coacting with a toothed segment 43 and a connecting rod 44 is operatively connected by one end to the lever 41 and by its other end to the upper rear portion of frame of the binder. As will be 100 readily seen the binder may be tilted by swinging the lever 41.

In order to adapt my device for use in plowing or mowing I remove the standard 23 and position in the bearing 45 a shaft 105 45' provided with a downwardly extending forked standard 46 between the lower ends of which is mounted a bearing wheel 47. The upper end of this shaft is mounted for rotation in the bearing 45 and secured to its 110 upper end is a lever arm 48 adapted for attachment with the steering rod, which is de-

tached from the binder frame for that purpose.

5 Swingly mounted by their forward ends is a pair of plow beams 49 and carried by the rear end of these beams are plows 50. A pair of hand levers 51 are provided for raising and lowering the plow beams as shown.

10 Extending downwardly from the side member 17 of the frame intermediate its length, is a bracket 52 in the lower end of which is journaled a shaft 53 upon one end of which is keyed a beveled gear 54 and upon the other end of which is keyed a disk 15 55 having an eccentric pin 56. Connected by one end to this bracket and extending transversely across the machine is a rod 57 the opposite end of which is connected to the shoe 58 of a cutter bar 59. This shoe is 20 further supported in place by a draw bar 60 one end of which is pivotably connected to the shoe while the opposite end is connected to the forward end of the frame member 11. Reciprocally mounted in this 25 cutter bar is the customary cutting blade 61 to the inner end of which is connected one end of a pitman rod 62 the other end of which is operatively connected to the eccentric pin 56. As a means for rotating the 30 shaft 53 to actuate the mowing element I have provided a transversely extending shaft 63 which is journaled in suitable bearings carried by the frame and which is provided at one end with a gear 64 meshing 35 with the gear 32 and at its other end with a bevel gear 65 meshing with the bevel gear 54 of the shaft 53. When the machine is to be employed for purposes other than mowing, the bracket 52 and the draw bar 60 are 40 disconnected from the frame thus entirely removing the mower element from the machine.

45 From the foregoing description taken in connection with the drawings, it will be apparent that I have provided a traction engine provided with plows and a mowing element either of which may be rendered inoperative when desired, said engine being provided with a detachable guide wheel 50 which may be replaced by a standard adapted to swivelly engage with a binder whereby the engine may be employed as a propelling means for the binder. It will also

be apparent that I have provided a novel and efficient steering mechanism for traction engines of the above described character.

55 It will of course be understood that minor changes in details of construction may be made if desired without in the slightest degree departing from the spirit of my invention.

60 What I claim is:—

1. The combination with a front and rear wheeled frame, of a universal connection 65 between the frames, means carried by the rear frame for swinging the front frame horizontally and means carried by the rear frame for tilting the frame.

2. The combination with front and rear frames, wheels supporting the frames, a 70 forwardly and downwardly curved standard at the front end of the rear frame, ball and socket connection between the said standard and front frame, a steering rod 75 rotatably mounted upon the rear frame and having a hand wheel, a guide rod pivoted to the front frame and actuated by said steering rod whereby the front frame may be guided when advancing either forwardly 80 or rearwardly, and means for tilting the front frame.

3. The combination with front and rear frames, wheels supporting the frames, a 85 forwardly and downwardly curved standard at the front end of the rear frame, ball and socket connection between the said standard and front frame, a steering rod rotatably mounted upon the rear frame and having a hand wheel, a guide rod pivoted to 90 the front frame and actuated by said steering rod whereby the front frame may be guided when advancing either forwardly or rearwardly, a motor on the rear frame and having gear connections with one of the 95 wheels supporting the same whereby the said frames may be advanced in unison, and means carried by the rear frame for tilting the front frame.

100 In testimony whereof, I affix my signature, in presence of two witnesses.

ALBERT F. CRESIEN.
